UNITED STATES PATENT OFFICE

JOHN B. GOLDSBOROUGH, OF CROTON-ON-HUDSON, NEW YORK

CONSTRUCTION OF RETAINING WALLS

Application filed November 16, 1928. Serial No. 319,876.

This invention relates to the construction of walls for retaining the earth at the sides of excavations while they are being made and for thereafter serving as a form for or in combination with suitable material such as concrete, as permanent walls at the sides of the excavations.

A method of lining excavations which is in present use, consists of bracing the sides 10 of the excavation with vertical planks spread apart by screw jacks or wedged struts interposed between horizontal wales engaging the surfaces of the planks. This construction is only temporary at best and requires a great 15 many pieces of large and expensive lumber in order to obtain sufficient bracing. Furthermore, such an arrangement presents structural difficulties if an attempt is made to utilize it as a form for a permanent concrete 20 wall, since the mass of lumber will not permit of a strong wall of regular cross-section such as may be necessary in wet earth or quick-sand, for example.

It is the principal object of this invention 25 to provide a wall which may in the first instance serve as a temporary structure to retain and brace the earth at the sides of an excavation while it is being made, and which can thereafter serve as a form for or be incorporated in a permanent structure, which 30 it reinforces.

A further object of this invention is to provide a method of retaining wall construction 35 in which uniform pieces formed of any suitable construction material may be used for any conditions of construction.

Other objects and advantages of this invention will become apparent from the following description of the preferred embodiment illustrated by the accompanying drawings, in which like reference characters designate like parts in the several views.

In the drawings:

Figure 1 illustrates one method of constructing a retaining wall in accordance with this invention;

Fig. 2 illustrates a completed retaining wall;

Fig. 3 shows the preferred arrangement 50 for bracing opposite sides of an excavation;

Fig. 4 shows a modified form of construction for use in wet soil;

Fig. 5 illustrates another form of construction in vertical section;

Fig. 5a is a view in elevation of the modification shown in Fig. 5. 55

Fig. 6 shows a retaining wall constructed with a preferred form of metal elements;

Figs. 7 and 8 are illustrative sections of the construction shown in Fig. 6. 60

Figs. 9 and 10 show the method of erecting the metal forms;

Figs. 11, 12 and 13 illustrate construction parts used in erecting the metal elements; and 65

Fig. 14 is a modification of the wall of Fig. 6 using a built-up element of wood or other construction material.

Referring to Fig. 1 of the drawings, numeral 1 designates a vertical member, preferably a steel I-beam, which is driven vertically into the ground as shown, together with successive other I-beams along the line of the proposed excavation. As the excavation progresses, relatively short pieces of construction material 2, of wood, concrete, steel or the like, are placed across the space between beams 1 so that the ends thereof engage the outer flange of the beam. These pieces 2 are preferably successively introduced one 70 beneath the other so that they form a continuous wall as the excavation progresses, and spaces or slits are preferably left between them for the purpose of tamping the material 3 subsequently filled into the space 4 left 75 behind pieces 2. Figs. 2 and 3 illustrate respectively a retaining wall and a lined excavation, and both show the filling 3 which has been introduced, and which may be earth, stone, concrete or the like. If concrete is used, beams 1 and pieces 2 may be removed after the excavation has been completed if desired, thus leaving a permanent concrete 80 wall. In Fig. 3 cross-braces 5 are used in the usual manner. 85

In Fig. 4, a form of construction is illustrated which is particularly useful in wet soil. I-beams 1 are driven in the manner described, and if the surface of the soil is dry enough, the above-described structure may 100

be used until wet soil is encountered. In such a case, cross bars 6 of any suitable material, are inserted behind the inner flanges of adjacent I-beams, and poling pieces 7 are driven diagonally downward as shown in Fig. 4. The excavating is then continued to approximately the bottom of pieces 7, when the process is successively repeated to the required depth. This method has the advantage that the wet soil is supported during the excavating process, whereas it would otherwise cave in, and that the excavation may progress to a suitable depth by convenient stages without being hindered by the bracing and cross-bracing at present employed, inasmuch as cross-bars 6 are securely held behind the flanges of I-beams 1 and do not project beyond the walls of the proposed excavation.

Fig. 5 illustrates a modified structure in which short vertical members 8, such as I-beams, are used in staggered arrangement, and which are removed together with the pieces 2, which the forms support, as the excavating reaches a depth equal to the length of each member 8. In such a case, the compacted filling such as concrete 3, previously introduced behind pieces 2, is relied upon to support the remaining contiguous earth.

In some localities the retention of wood in underground construction is prohibited on account of the settlement of the earth as the wood rots, with possible damage to buildings, pipes, conduits or the like in the vicinity. In such cases the removal of such wood as may be required during operations is often times difficult and adds materially to the cost of the work. Accordingly, in Figs. 6 to 10, a form of construction is illustrated which may in the first instance serve as a temporary structure to retain and brace the earth at the sides of an excavation while it is being made, and which can thereafter be incorporated in a permanent structure, which it reinforces, and in which no part of the temporary structure will be exposed to deterioration when formed into the permanent structure. The necessity for removing any of the temporary structure is avoided with consequent saving of expense and gain in time of construction, and there is no danger of settlement and resultant damage to foundations, pipes and other objects due to rotting away of wooden elements or rusting of iron ones.

In Fig. 6 is shown a form of permanent wall erected according to this invention in which channel-shaped metallic-sheeting pieces 9 are substituted for the flat pieces 2 illustrated in the previous figures, but which are arranged in the same manner and for the same purpose as the latter behind the flanges of I-beams 1 or the like, which have been driven vertically into the earth each in the manner described. As the excavating progresses, pieces 9 are successively introduced one below the other with the edges of their

flanges engaging the flange of the I-beam 1 so as to leave longitudinal spaces therebetween. As shown particularly in Fig. 7, spaces are left between pieces 9 for compacting the earth behind them by tamping between them. Heavy metallic channel-shaped wales 10 are preferably employed for bracing the I-beams, and against which bear temporary wooden wales 11 which are engaged by the wooden cross-struts 5.

Various ways of effecting the spacing of the channel pieces 9 may be employed, one of which is shown in Fig. 9, wherein the length of the excavation requires a plurality of lengths of the sheeting channels 9 at each successive limit of height. In order that adjacent tiers of the sheeting channels 9 may be kept in correct alignment, connecting plates 12 (Fig. 11) lap the adjoining ends of the flanges of the adjacent channels that are at the same level. Bolts 13 pass through matched holes in the ends of the plates 12 and the ends of the channel flanges which they lap. By tightening the nuts 14 on the bolts 13, after the joined sheeting channels 9 have been arranged to mutually extend the continuity each of the other, sufficiently accurate alignment of the channels 9 will be maintained.

To afford an easy, convenient and inexpensive mode of forming and preserving the horizontal tamping slits between successive tiers of the sheeting channels 9, spacers 15, one of which is shown on an enlarged scale in Fig. 12, may be employed. The spacer 15 consists of a cylindrical shell which may be quickly formed by merely cutting a piece of sheet metal and bending it into a slit cylinder, as shown. The height of the cylinder shell 15 is such as to give the desired width to the tamping slits between the sheeting channels 9. Encircled by the outer shell 15 of the spacer shown in Fig. 12 is an inner cylindrical rod 16, which is adapted to pass through matched holes in the overlapping flanges of upper and lower sets of channel pieces 9, being particularly suited for use in corners of meeting walls or wall-bracing structures, as indicated in Fig. 9. Being of sufficient length to extend above and below the spaced flanges of the channel pieces 9 which are in tiers one directly over the other, the rod 16 is adapted to receive pins or nails 17 in apertures near its opposite ends.

At the coupling joints of continuing lengths or sections of the channel pieces 9, the spacers 15 may be used, if desired, as indicated at the left in Fig. 9. As shown in such an arrangement a connecting plate 12 lies on the top flange of the lower channel piece 9, and the spacer 15 is interposed between the connecting plate 12 and the bottom flange of the upper channel piece 9. The rod 16 passes through the connecting plate 12, the bottom flange of the upper channel 130

piece 9, through the spacer 15, the connecting plate 12 on the top flange of the lower channel pieces 9 and through this flange as well. The nails 17 extend through the protruding 5 ends of the rod 16, securely interlocking the parts.

A simple spacing device which may be used where the adjoining ends of aligned channels are overlapped by a vertical flange 10 of one of the I-beams 1, as shown in Fig. 10, is the U-shaped member 18 shown in Fig. 13. The U-shaped members 18 are slipped over the opposite edges of one of the flanges of the I-beams, and one leg of each U-shaped member 15 is allowed to roll on that flange until the other leg of the U-shaped member swings against the opposite face of the flange. Thereupon further rolling of the first mentioned leg is prevented by the flange which 20 lies between the legs of the U-shaped member 18. The ends of the channel pieces 9 are placed on those legs of the U-shaped members 18 which lie outside of the flange of the I-beam 1. The loads so imposed on these 25 legs tend to further rotate the U-shaped members about their legs on the other side of the flange. This results in both of the legs of each of the U-shaped members gripping the flange of the I-beam 1 more tightly, 30 preventing displacement of the U-shaped members 18. With the channel pieces 9 supported elsewhere and influenced to remain in their normal positions, they will also be held in spaced relation to each other on the 35 I-beam 1. This arrangement may be used wherever it is adaptable and found to be convenient.

With the I-beams 1, the wales 10 and the channel pieces 9 arranged and supported as 40 hereinbefore set forth, a temporary bracing structure or framing is created, which is adapted to hold the sides of the excavation intact while the retaining wall is being constructed. Form boards 19, shown in phantom in Fig. 7 are built up as the work proceeds, whereby masonry or foundation material 20, such as concrete, may be poured into the temporary bracing structure to form 45 a retaining wall. As such a wall is being constructed, the concrete 20 fills the spaces between the I-beams 1, and, due to the channel-shape of the pieces 9, the concrete also flows back of the vertical flanges of the I-beams. The channel-shape of the wales 10 50 allows the concrete 20 to occupy the space in front of the flanges of the I-beams 1, so that the front face of the wall may be constructed without disturbing the wales 11 and struts 5 until after the concrete has set when they 60 will be removed with the form boards 19, the metallic structure including pieces 9, beams 1, and wales 10 having become part of the permanent wall as reinforcement. Vertically and horizontally disposed concrete-reinforcing rods 21 and 22 are imbedded in the 65

concrete 20 in front of the I-beam flanges. At the rear or inner side of the retaining wall, horizontal reinforcing rods 23 are imbedded in the concrete at the junctions of the continuing channel pieces 9, thereby 70 strengthening the wall at the joints of the channels.

In Fig. 14, the sheeting channels 9a have been constructed of wood, and comprise a web board 9b and upper and lower flange-forming boards 9c and 9d, respectively. From this view, it will be readily understood that when all metal material is unavailable, or for other reasons is undesirable, the retaining wall may be constructed from other material. Further, if desired, form boards such as 19 in Fig. 7, may be placed along the inner flanges of I-beams 1 of the structures shown in Figs. 1 to 5 inclusive, and the resulting space filled with concrete or other construction material in the manner above described, thus forming a more permanent wall. In such a case, pieces 1, 6 and 7 are left in and form part of the structure, reinforcing the same. It will also be understood that various other changes in the structural details of the invention may be made without departing from its principle as defined in the appended claims.

I claim:

1. The method of constructing a retaining wall which consists in sinking substantially vertical members into the ground, excavating the earth at one side of the vertical members and between the same, placing successively below each other as the excavation proceeds horizontal, channel-shaped, sheeting members on the other side of the vertical members with their flanges toward the members and filling the sheeting members and the spaces between the vertical members with suitable material to form with said members a permanent, reinforced wall.

2. The method of constructing a retaining wall which consists in sinking substantially vertical members into the ground, excavating the earth at one side of the vertical members and between the same, placing successively below each other as the excavation proceeds horizontal, channel-shaped sheeting members on the other side of the vertical members, spaced from each other and with their flanges toward the members, compacting the earth behind the pieces through the spaces between them, and filling the spaces between the vertical members and the pieces with suitable material to form with said members a permanent wall.

3. A wall partially formed of parts of a structure for bracing the side of an excavation, said structure comprising upright ground-penetrating members, channeled members on opposite sides of said upright members extending lengthwise of the wall, and foundation material between said up-

right members, and extending through the channeled members to unite the portions that are disposed between successive upright members.

5 4. A wall partially formed of parts included in a structure for bracing the side of an excavation, said structure comprising upright ground-penetrating members, channeled members on opposite sides thereof extending lengthwise of the wall, the channeled members on one side of said upright members being vertically spaced from each other, and foundation material between said upright members extending through said 10 channeled members and unified with the like material between said upright members.

In testimony whereof I affix my signature.
JOHN B. GOLDSBOROUGH.
